UNITED STATES PATENT OFFICE

163,176

DOLL

Adalene Garen, Peoria, Ill.

Application April 17, 1950, Serial No. 9,274

Term of patent 7 years

(Cl. D34—4)

To all whom it may concern:

Be it known that I, Adalene Garen, citizen of the United States, residing in Peoria, in the county of Peoria and State of Illinois, have invented a new, original, and ornamental Design for a Doll, of which the following is a specification, reference being had to the accompanying drawing, forming a part thereof.

Fig. 1 is a front view of a doll showing my new design;

Fig. 2 is a rear view of the doll;

Fig. 3 is a side view of the doll.

I claim:

The ornamental design for a doll, as shown.
ADALENE GAREN.
